UNITED STATES PATENT OFFICE.

OSCAR A. ANDERSON, OF CAMBRIDGE, MASSACHUSETTS.

LOOM.

Application filed December 5, 1923. Serial No. 673,772.

This invention relates to a loom for special weaving purposes, particularly for weaving strands of twisted paper which are glued slightly during the process of twisting so that they form relatively stiff strands of any desired size. These are used largely for making the fabric with which baby carriages are usually covered. It is to be understood that while this invention is particularly useful for weaving that kind of fabric it can be used for other materials.

The principal feature of the invention is the provision of means whereby a single ply multiple shed is formed by deflecting every alternate strand of the warp in opposite directions away from their natural courses so as to cause the warp to cross between the deflecting means and the holding means and for introducing simultaneously two strands of weft or filling which I call the stake on opposite sides of the crossing points. It is not necessary that every alternate strand be deflected in one direction for, with certain kinds of weaving, this is not done and furthermore it is not always necessary to insert both of the filling strands between the two warp strands as for certain kinds of weaving one of them can be inserted at the same points on the outside of the warp, that is, on the same side of both warps. According to this invention I have two separate weaving points in alignment with each other along the fabric, preferably one directly over the other when the fabric is fed down in a vertical direction. Through these two weaving points I pass at one motion two tubular stake carriers containing two stakes therein. With the strands of the warp crossed, as stated, these two strands of filling or stakes, as I call them, are introduced in such a way as to be separated from each other by the warp. Instead of changing the shed after the stake carriers have traversed it in one direction it is changed only after the complete reciprocation of the carrier. In fact the shed is not changed at all in the ordinary sense, as it is always the same when the carrier is introduced. This involves a material simplification which is capable of general use. Thus for each motion of the loom two filling strands are woven in and twice as much cloth is woven as would be the case if only one were inserted at a time. Therefore a great increase in the product is obtained.

The invention also involves two sets of warp fingers, one set revolving, preferably, and the other set reciprocating but working in exact synchronism for separating the warp strands. The hollow tube stake carriers are a feature of importance because the stakes are threaded through them and they are provided with means for preventing them from being drawn out backwards and the loom is provided with means for holding the ends of the two stakes when the stake carriers pass through. Then the stake carriers are withdrawn leaving the stakes in the fabric and the stakes are cut off automatically. The fabric is drawn through the loom by a pair of rolls controlled to operate with the motion for separating the warp strands and arranged to keep proper tension on the fabric at all times. The invention is capable of ordinary block weaving and also diamond work. For the latter a second set of sliding fingers for operating the warp are situated above the sliding fingers and I prefer to operate them by hand.

Other objects and advantages of the invention will appear hereinafter.

Reference is to be had to the accompanying drawings, in which—

Fig. 1 is a plan of the end of the loom and the means for operating the stake carriers;

Fig. 2 is a side view of the latter;

Fig. 3 is an end view of the same;

Figs. 4 and 5 are front views of opposite ends of the loom on enlarged scale; (These two figures should be considered together).

Figs. 6 and 7 are end views of the opposite ends of the loom;

Fig. 7^a is a view of the means for reciprocating the stake carriers.

Fig. 8 is a cross-section on the line 8—8 of Fig. 7 showing the shears;

Fig. 9 is an enlarged detail view of the stake gripper;

Fig. 10 is a diagrammatical perspective view of the weaving portion of the loom without the frame showing the manipulation of the warp strands;

Fig. 11 is a similar view of a portion of the same showing the stake carriers with the stakes therein;

Fig. 12 is an edge view of the latch for operating the shears;

Fig. 13 is a side view of the same showing the dial that it operates;

Fig. 14 is a side view of the carrier block with its two stake carriers;

Fig. 15 is an end view of the same;

Fig. 16 is an end view somewhat diagrammatic showing the manipulation of the warp in a modified way for weaving block or diamond work;

Fig. 17 is a front view of the same;

Fig. 18 is a view of the fabric showing the block work produced thereon; and

Fig. 19 is a side view of a bracket at the end of the frame showing the reels for supporting the stakes;

I have shown the invention as involving two frames. One of these frames comprises three legs 20 or standards having a top 21 supported thereby. This top runs along the tops of the legs being fixed to each of them so that the whole structure is held firmly together. The top 21 is of T-shaped form throughout its length constituting a guide or ways for a sliding table 22 adapted to reciprocate throughout the length of this frame. This table 22 is about half the length of the frame preferably, while the ways 21 extend throughout the length of it.

This frame is provided with a main shaft 23 having tight and loose pulleys 24 thereon adapted to receive power from a counter-shaft, although it can be run by separate motor, as desired. But I have shown an ordinary planer table belt shipper 25 for reversing the shaft 23 and on the table 22 I have shown planer type belt shipper dogs 26 for engaging the belt shipper and automatically reversing the motion at each end of the stroke so that it will reciprocate continuously and repeatedly as long as that power is connected. In other words, I have adopted one of the well known schemes for driving a planer table which is particularly adapted for this invention.

Fixed on the table 22 is a block 28 provided with a pivoted spring latch 29 which projects down and is adapted to move freely to the right in Fig. 2 without hindrance but is provided with a stop to prevent its moving to the left. Directly below this latch 29 is a ratchet wheel 30 adapted to be engaged by the latch and turned a definite portion of a revolution every time the table moves back. This block 28 is adjustable on the table and can be set to operate the ratchet wheel at any point in the reverse motion of the table. Ordinarily it is set so as to operate nearly at the end of the reverse stroke of the table.

The ratchet wheel 30 is mounted on a shaft 32 on which is provided a bevel gear 31 meshing with a bevel gear or pinion on a longitudinal shaft 33. This shaft 33 extends through the adjacent loom side 35 which constitutes one end of the loom proper. The two loom sides 35 constitute the other of the two frames above mentioned. They are held together by cross bars 36 and also

by other features which will be described later. On the shaft 33 is fixed a roll 34. Two of these rolls are shown constituting a pair of cloth rolls and supported on the two end frames 35.

The shaft 33 is provided with a gear 38 and the shaft of the other roll 34 with a gear 39 meshing with each other and of the same size so that these two rolls rotate toward each other and downwardly at their contacting surfaces for the purpose of drawing down the woven fabric between them. The gear 39 through a pinion 39^a operates a gear 40 which, in turn, operates a smaller gear 41 fixed on a shaft 53. On this shaft 53 is fixed a sprocket wheel 42 which by means of a chain 43 operates a smaller sprocket wheel 44 fixed on a stud 47. On this stud 47 is a crank 45 which has an adjustable crank pin for engaging in a slotted arm 46 fixed on a shaft 37 that extends across the loom lengthwise. On this shaft also there are two gear segments 48 one located at each end of the loom. These gear segments therefore are rocked forward and back every time the shaft 37 is oscillated by the rotation of the gear 43 through a complete revolution which is accomplished at each motion of the table forward and back.

The gear segments 48 mesh into a pair of racks 49 on the bottom of a horizontal slide 50. This slide is mounted in transverse guides 51^a on the frames 35 of the loom and therefore moves back and forth once for each operation of the loom. This frame 50 is provided with a series of rigid warp engaging fingers 51 preferably spaced apart a distance equal to their width and their width being equal to the distance between two strands of the warp of the fabric to be woven.

The shaft 52 extends throughout the length of the loom and is provided with a cylinder 54 thereon having a plurality of rows of rigid fingers 55 projecting radially therefrom and rounded on their forward surfaces near their ends. These fingers are spaced exactly like the fingers 51 but alternately with respect to them. All the fingers 55 are spaced alike and those of each row are arranged at the same distance from the end of the roll. The timing of the shafts 53 and 37 is such that every time the slide 50 moves in a set of fingers 55 will move down into a position in the same plane with them, as shown in Fig. 10, the fingers 55 alternating with the fingers 51. In the form shown in which there are four rows of fingers 55 the cylinder 54 rotates a quarter of a revolution for each reciprocation of the table. It will be seen that every alternate strand is forced forward by the fingers 55 and the other strands backward by the fingers 51 so that they cross and pass by each other. The strands are in two series supported by

frames 56 above spaced considerably apart forming a single ply multiple shed. It may be stated at this time that the filling is introduced above and below the crossing points in the shed. (See Fig. 10.)

It will be understood from what has been said that the rotary motion of the cloth rolls 34 is intermittent. The shafts on which they are mounted are provided with 10 any desired friction devices if desired to prevent backward motion or motion after the power is disconnected from them. They draw the fabric down between them. This fabric is formed as stated by two series of 15 warp strands W from two series of spools 59 mounted on a shelf 57 at the top of the loom and passing down over guide rolls 58 and into a pair of frames 56. These frames 56 are mounted in stationary position and extend across the loom helping to strengthen it. Their principal function is to keep the two series of strands separated down to a point just above the highest point of the motion of the fingers 55 so 20 that by manipulations above described a wide shed can be formed in a comparatively narrow space.

On the reciprocating table 22 is located a block 60. This block has two passages all 25 the way through it parallel with each other and parallel with the direction of motion of the table for the purpose of receiving a pair of stake carriers 61. These stake carriers are of tubular form uniform throughout 30 and of a length long enough to extend clear across the loom proper. The carrier block is provided with a pair of screws 62 extending into the passages for the stake carriers for securing the shuttles in position 35 and permitting their adjustment. The stake carriers are also provided with a pair of casings 63 in which are located inclined pins 64 each pressed inwardly by a spring 65 and each having a point 66 which turns 40 forward in the direction of feed of the stake. The stake S is inserted in these two stake carriers from the right hand end in Fig. 45. Of course the pins 66 do not oppose the motion of the stake through the stake carriers in this direction but they prevent 50 its withdrawal. The stake is forced in until the end of it comes through the forward end of the carrier and projects therefrom.

It is to be understood that the stake is 55 supplied in a continuous long length from a pair of spools 67 located at the extreme rear end of the frame 21 and guided in a straight line from a point at the rear of the table through guides 68. Now it will be 60 seen that, with the stakes threaded through the stake carriers and the table starting from the position shown in Figs. 1 and 2, the feeding of the table forward in the direction of the arrow in Fig. 2 will cause the stakes 65 to be forwarded with the stake carriers and

unwound from the spools 67. On the backward movement, it being understood that the projecting ends of the stakes are held at the other side of the loom, the stake carriers simply move back along the stakes 70 without disturbing them and the pins 66 get a new grip at points farther back on the stakes and are ready to forward the stakes again. Although this is a reciprocating motion and the operation is intermittent yet it 75 is continuous in the sense that no adjustment has to be made and no attention paid to the withdrawing of the stakes from their rolls. These stakes it will be understood are frequently made of twice the size of the so-called warp strands of the fabric but of the same material preferably, though not necessarily.

On the forward end of the table 22 is a block 70 which carries a long bar 71. On the back side of this bar are fastened two cam blocks 72 having opposite inclined cam surfaces. They project beyond the end of the table 22, far enough to come to a position at the extreme opposite side of the 80 loom when the table is projected as far as it can be toward the loom. At that time one cam block 72 engages and operates one of a pair of levers 73 on a shaft 74 at opposite sides of the loom. This lever has 85 another arm pivoted to a plate 75 which is mounted on a pair of horizontal guide bars 76 carried in a projection 77 on that end of the loom, as shown in Fig. 6. These 90 guide bars extend through the projection 77, the opposite vertical surface of which is formed to provide two jaws for gripping the stakes. For this purpose it has two depressions 78 in that surface located the same 95 distance apart as the stakes. On the end of the guide bars 76 is fixed a gripping jaw 79 to move with these bars and provided with corresponding depressions. This 100 arrangement is provided for the purpose of gripping the projecting ends of the two 105 stakes when the stake carriers are projected nearly to the back side of this stake gripping apparatus. It is while the stakes are gripped between these two jaws that the 110 stake carriers are drawn back leaving the stakes in the fabric. The other cam 72 and lever 73 act to release the gripper at the 115 other end of the stroke.

On this bar 71 there is fastened a latch block 80 having thereon a pivoted latch 81 and a spring 82 for holding the latch up against a stop 83. Above the path of this reciprocating latch block 80 at the near side of the loom is a ratchet dial 84, the teeth 120 of which project down into a position to depress the latch as it passes under it. These teeth have radial rear ends which the latch engages. This causes the dial 84 to be rotated on a stud 85 fixed on this end of the 125 loom and in rotating through the space of 130

one tooth a tooth at the top engages and raises a roll 86 mounted on a rod 88 which is held down by a spring 87 so that the roll 86 always rides on the surfaces of the teeth 5 of the dial. This rod 88 is connected with two shear blades 90. These are pivoted at 91 on the frame, the two pivots being just as far apart on the centers as the two stakes in the fabric. The points at which the rod 10 88 is pivoted to the two levers are at the same distance apart so that these levers have a parallel motion. Every time they are raised at their right hand ends in Fig. 7 the opposite ends come down to co-operate 15 with another pair of shear blades 92 and cut the two stakes just after the shuttles have been fully withdrawn.

Operation.

20 The operation has been described in connection with the description of the various parts but will be gone over again briefly. The so called warp strands W of twisted paper, wound on the two series of spools 59 are passed down over the roll 58, separated from each other longitudinally of the loom and then they are separated into two series by the frames 56 through which they pass. They are kept separated wide apart 25 by these frames and pass down normally to the woven fabric below held by the rolls 34. Now when the table 22 moves back to the end of its stroke toward the right the shaft 32 is rotated a part of a revolution and likewise the rolls 34. This draws the fabric down while the fingers 51 are moving back and the fingers 55 are turning through a quarter turn. Therefore the fingers do not interfere with the straight passage of the 30 warp fibers from the lower ends of the frames 56 to the top of the fabric below, but now, as the shaft 32 starts to rotate, the slide 50 is caused to move inwardly and the roll 54 to rotate further until the next set 35 of fingers 51 assume the position shown in Fig. 10 and the fingers 55 move back to that position. This, it will be observed, is at the time when the table is moved back to its extreme position and the stake carriers 61 withdrawn. It now reverses automatically 40 and the table is slid forward not affecting the shaft 32 and the fingers 51 and 55. One effect of this is to force the two stake carriers into the two spaces in the shed of the fabric one over the other as shown in Fig. 11. One of the stake carriers moves in over 45 the ends of the two sets of the fingers but the other has no support from the machine all the way across except a projection 99 on the frame 35 which is provided for that purpose. When the table moves to its extreme forward position one cam 72 operates one lever 73 and causes the gripper jaw 78 50 to move to the position shown in Fig. 6 and grip the projecting ends of the two stakes.

Now the table is reversed and moves back with the stakes still gripped. The stakes therefore remain stationary while the stake carriers move back along them.

As the stake carriers reach nearly the end 70 of their stroke backwardly the latch 81 operates the dial 84 and causes the two shear blades 90 to swing down and shear the stakes at that side of the loom just at the end of the reverse stroke. This latch is designed to 75 move the dial throughout the space of one tooth and the teeth are so designed that the roll 19 will be let down again into the lowest part of the next tooth during this motion so as to raise the shear blades again by 80 the action of the spring 87. At this time the other cam 72 engages the other lever 73 and releases the stake gripper. Now the table is reversed and moved back. The stake pushed into the upper shed does not become locked into place until the fabric has advanced one motion of the loom and the new shed is formed. The forming of the new shed is what locks the stake in, said stake now being in the first space below the 90 lower set of fingers.

The weaving above described is the ordinary basket weaving which is uniform throughout the length and breadth of the fabric. If diamond or block work is desired an additional sliding frame 100 is set 95 into a pair of horizontal notches 101 in the opposite ends of the frame. This slide is provided with fingers 102 similar to the fingers 51 spaced in any desired way to provide the diamond or block weaving at any desired point and throughout any desired extent in the width of the fabric. This frame is so located that when pushed in the fingers project the forward strands of the 100 warp inwardly so that the upper stake instead of passing between them will pass outside of them, or in front of them more properly speaking. Therefore the form of the weaving is changed as shown in Fig. 18. 110 Here two sets of warp threads are shown in heavy and double light lines merely to distinguish them. They are just alike but follow different courses. The course of the 115 weave is changed from in front of one stake and back of the next to in front of one and back of two. This is caused by the upper set of fingers 102. This is provided according to the present invention to be set in place and operated by hand as often as may be desired to secure the desired results in the fabric. It is of course not used all the time through any woven fabric preferably and therefore I prefer at the present time not to operate it automatically. An automatic device for operating it can be provided but would add materially to the complication of 120 the machine.

The method of weaving herein disclosed 130 is a material improvement over the way in

which these materials are now woven in practice. As a matter of fact I have reversed the operation by using the stake as filling whereas in the ordinary methods the stakes are employed for warp and the smaller strands designated W in these drawings as filling. The fabric in this way can be woven into very wide widths and a great increase in speed is secured over the present methods even if only one stake were inserted at a time, but in my invention two can be provided and if desired, even a third one could be introduced in the form illustrated in the diamond weaving diagrams. By introducing two stakes the production is doubled and the hand work now employed in operating the crude machines on the market is practically eliminated except when it is desired to produce diamond weaving and even that is greatly simplified. At the same time I have provided an extremely simple stake carrier and improved other features of the loom.

Although I have illustrated and described only a single form of the invention and only two styles of weaving I am aware of the fact that many modifications can be made in both without departing from the scope of this invention as expressed in the claims. Therefore I do not wish to be limited to the exact details of construction herein shown and described nor to either of the forms of weaving illustrated but what I do claim is:—

1. In a loom, the combination with means for supporting two series of warp strands, of rotary means for moving one series of strands inwardly toward the other, and sliding means for moving the other series inwardly toward the other to cross them and form a single ply multiple shed.

2. In a loom, the combination with means for forming a shed consisting of two series of warps crossing each other and each extending in a straight line all the way between its points of support on opposite sides of the line of crossing, of means for inserting a weft strand through the shed and withdrawing said means before any change in the shed, and means for simultaneously inserting a second weft strand on the opposite side of the line at which the warp strands cross.

3. In a loom, the combination with means for repeatedly forming a single ply multiple shed always in the same way with the warps crossing in two planes, of means for introducing the weft strands two at a time on different sides of the crossed warp strands into the same parting of the warp at each operation of the loom.

4. In a loom, the combination with means for guiding and feeding warp strands, of means for manipulating said strands to form a single ply multiple shed consisting of straight warps, and means for introducing

a pair of stake carriers simultaneously for leaving the two stakes or filling strands in the shed at different points along the fabric upon the withdrawal of the stake carriers at one operation of the loom.

5. In a loom, the combination with means for crossing two sets of warp strands in straight lines to form the shed, of two stake carriers arranged in the plane of the crossing warp of the shed and located in position for entering on opposite sides of the crossed warp strands and at different points lengthwise of the fabric.

6. In a loom, the combination with means for supporting two sets of warp strands spaced apart laterally, and means for forcing the strands of each set beyond each other to cross them and form a single ply multiple shed, of means for simultaneously introducing two stake carriers on the same side of the loom on opposite sides of the line at which the warps are crossed.

7. In a loom, the combination with a plurality of separated guides for guiding sets of warp strands into the loom at a material distance apart crosswise of the fabric, means for crossing the strands, a pair of cloth rolls for engaging the fabric produced and feeding it to draw the warp strands through said guides, and means for holding a plurality of hollow stake carriers and moving them into the spaces between the series of warp strands, the stake carriers having means for engaging the stakes therein and feeding them positively forward and releasing the stakes when the stake carriers move back.

8. In a loom, the combination with a pair of separated guides for guiding two sets of warp strands into the loom, a pair of cloth rolls for engaging the fabric produced and feeding it to draw the warp strands through said guides, means for holding a pair of hollow stake carriers and moving them into the space between the two series of warp strands, and means for pushing each set of warp strands inwardly toward the other and beyond it so as to cross the strands in a position to receive the two stake carriers on opposite sides of the line of crossing of the warp strands.

9. In a loom, the combination with a pair of guides for guiding two sets of warp strands, two sets of warp engaging fingers alternately spaced with respect to each other and accurately spaced with respect to the spacing of the warp strands, means for pushing each set of warp strands inwardly toward the other and beyond it so as to cross the strands in a position to receive two stake carriers on opposite sides of the line of crossing of the strands, and means for holding a pair of hollow stake carriers and moving them into the space between the two series of warp strands, the stake carriers having

- means for engaging the stakes therein and feeding them positively forward and releasing the stakes when the stake carriers move back.
- 5 10. In a loom, the combination with a pair of separated guides for guiding two sets of warp strands at a material distance apart into the loom, two sets of warp engaging fingers alternately spaced with respect to 10 each other and accurately spaced with respect to the spacing of the warp strands, means for reciprocating one set of fingers and rotating the other set at the same time to cause them to cross the warp, and means 15 for holding a pair of hollow stake carriers and moving them into the spaces between the two series of warp strands on opposite sides of the line along which they cross, the stake carriers having means for engaging the 20 stakes therein and feeding them positively forward and releasing the stakes when the stake carriers move back.
11. In a loom of the character described, the combination with a pair of guides for 25 guiding two sets of warp strands through the machine in different planes, a cylinder, a plurality of series of fingers mounted on said cylinder, means for rotating said cylinder intermittently, said cylinder being 30 located in position for these fingers to engage the nearer set of warp strands and push them beyond the other set.
12. In a loom of the character described, the combination with a pair of guides for 35 guiding two sets of warp strands through the machine in different planes, a pair of rolls for engaging the fabric and feeding it forward to draw the warp strands through said guides, means for operating said rolls 40 intermittently, a shaft parallel with the planes of the warp strands, a cylinder on said shaft, a plurality of series of radial fingers mounted on said cylinder and having beveled forward ends, means connected 45 with said cloth rolls for rotating said cylinder intermittently, said cylinder being located in position for these fingers to engage all the nearer set of warp strands and push them beyond the other set.
- 50 13. In a loom, the combination with a pair of guide frames located in fixed position for guiding the warp into the loom in two planes separated from each other, a series of rotary fingers located in position on one 55 side of the warp for engaging the warp strands on that side and pushing them inwardly, a slide located on the other side of the warp and having alternately arranged fingers for engaging the strands on 60 that side and pushing them inwardly, and means for simultaneously operating both sets of fingers to push their respective strands inwardly at the same time and form a shed.
- 65 14. In a loom, the combination with a pair of guides for guiding two sets of warp strands through the machine, a cylinder parallel with the planes of the warp strands, a plurality of series of fingers mounted on said cylinder, means for rotating said cylinder intermittently, said cylinder being 70 located in position for these fingers to engage the nearer set of warp strands and push them beyond the other set, a slide mounted to reciprocate directly toward and from the center of said cylinder and having fingers spaced apart alternately with respect to the fingers on said cylinder, and means for moving said slide inwardly when the cylinder is turned to move the first set of 75 fingers into engagement with the warp, whereby the second set of fingers will force the warp strands on that side beyond the other strands so as to form a shed.
15. In a loom of the character described, the combination with a pair of guides for 80 guiding two sets of warp strands through the machine, a pair of rolls for engaging the fabric and feeding it forward to draw the warp strands through said guides, means 85 for operating said rolls intermittently, a cylinder parallel with the planes of the warp strands, a plurality of series of radial fingers mounted on said cylinder, means connected with said cloth rolls for rotating 90 said cylinder intermittently, said cylinder being located in position for these fingers to engage the nearer set of warp strands and push them beyond the other set, a slide mounted to reciprocate directly toward and from the center of said cylinder and having 95 fingers in its plane spaced apart alternately with respect to the fingers on said cylinder, and means connected with the cloth rolls to be operated thereby for moving said slide 100 inwardly when the cylinder is turned to move the first set of fingers into engagement with the warp, whereby the second set of fingers will force the warp strands on that side beyond the other strands so as to form 105 a shed.
16. In a loom, the combination with a pair of guides for guiding the two sets of warp strands through the machine, a cylinder parallel with the planes of the warp strands, a plurality of series of radial fingers mounted on said cylinder and located in 110 position to engage the nearer set of warp strands and push them beyond the other set, means for rotating said cylinder intermittently, a slide mounted to reciprocate toward and from the cylinder, located on the opposite side of the shed and having fingers spaced apart alternately with respect to the fingers on said cylinder, a shaft rotatable from the cylinder and with it, an adjustable crank on the shaft, a shaft extending 115 across the loom having an arm thereon with a slot in it by which the crank is connected 120 with it to oscillate the last named shaft 125.

- as the crank turns, a pair of gear segments on the last named shaft, and a pair of racks on the slide meshing with said gear segments and operated thereby, whereby said slide 5 will move inwardly when the cylinder is turned to move a set of fingers into engagement with the warp, whereby the second set of fingers will force the warp strands on that side beyond the other strands so as to 10 form a shed.
17. In a loom, the combination with a pair of separated guides for guiding two sets of warp strands at a material distance apart into the loom, of a pair of cloth rolls for 15 engaging the fabric produced and feeding it to draw the warp strands through said guides, a reciprocating table, means for automatically reversing the motion of the table at each end of the stroke so as to cause a 20 constant reciprocation thereof, means on the table for holding a pair of hollow stake carriers and moving them into the spaces formed between the two series of crossing warp strands when the table advances, the carriers having means for engaging the stakes therein and feeding them positively forward and releasing the stakes when the carriers move back, a longitudinal shaft, means mounted on said table for rotating said 25 shaft when the table moves back to withdraw the stake carrier, means connected with said shaft for rotating the cloth rolls to feed the fabric, and means connected with said shaft for pushing each set of warp strands inwardly toward the other and beyond it so as to 30 cross the strands in a position to receive the two stake carriers on opposite sides of the line of crossing of the strands.
18. In a loom, the combination with a 40 pair of separated guides for guiding two sets of warp strands at a material distance apart into the loom, a pair of cloth rolls for engaging the fabric produced and feeding it to draw the warp strands through said guides, a reciprocating table, means for automatically reversing the motion of the table at each end of the stroke so as to cause a 45 constant reciprocation thereof, and two sets of warp engaging fingers alternately spaced with respect to each other and accurately spaced with respect to the spacing of the warp strands, of means connected with said shaft for pushing each set of warp strands inwardly toward the other and beyond it so 50 as to cross strands in a position to receive the two stake carriers on opposite sides of the line of crossing of the strands, means on the table for holding a pair of hollow stake carriers and moving them into the spaces formed between the two series of crossing warp strands when the table advances, the carriers having means for engaging the stakes therein and feeding them positively forward and releasing the stakes when the 55 stake carriers move back, a longitudinal 60
- shaft, means mounted on said table for rotating said shaft when the table moves back to withdraw the stake carrier, and means connected with said shaft for rotating the cloth rolls to feed the fabric.
19. In a loom, the combination with a pair of separated guides for guiding two sets of warp strands at a material distance apart into the loom, two sets of warp engaging fingers alternately spaced with respect to each other and accurately spaced with respect to the spacing of the warp strands, a shaft, and means connected with said shaft for reciprocating one set of fingers and rotating the other set at the same time to cause them to cross the warp as set forth, of a pair of cloth rolls for engaging the fabric produced and feeding it to draw the warp strands through said guides, a reciprocating table, means for automatically reversing the motion of the table at each end of the stroke so as to cause a constant reciprocation thereof, means on the table for holding a pair of hollow stake carriers and moving them into the spaces between the two series of warp strands when the table advances, the stake carriers having means for engaging the stakes therein and feeding them positively forward and releasing the stakes when the stake carriers move back, a longitudinal shaft, and means mounted on said table for rotating said shaft when the table moves back to withdraw the stake carrier, means connected with said shaft for rotating the cloth rolls to feed the fabric.
20. In a loom, the combination with a supporting frame, a longitudinally reciprocable table carried thereby, and means for reversing the motion of the table at each end of the stroke, of a carrier block carried with the table, a pair of tubular stake carriers located in said block, one directly over the other, means in the carriers for engaging a strand or stake of flexible material and feeding it forward with the shuttle but not backward when the table reverses, a loom frame adjacent thereto having means for forming a double shed, a double stake gripper at the opposite end of said loom, a rod fixed on the table, a cam on the extreme end thereof, and a lever arrangement on the loom in position to be operated by the cam and connected with the stake gripper to operate it, at the end of the forward stroke, to grip the ends of two stakes projecting from said stake carriers, whereby upon the withdrawal of the stake carriers the stakes will be left in the fabric.
21. In a loom, the combination of a supporting frame, a longitudinally reciprocable carrier block, a pair of tubular stake carriers located in said block, means in the stake carriers for engaging a strand or stake of flexible material and feeding it forward with the stake carrier but not back.

- ward, a loom frame adjacent thereto having means for forming a shed, a double stake gripper at the opposite end of said loom, a rod fixed on the table, a cam on the extreme end thereof, and a lever arrangement on the loom in position to be operated by the cam and connected with the stake gripper to operate it at the end of the forward stroke to grip the ends of two stakes projecting from said stake carriers, whereby upon the withdrawal of the stake carriers the stakes will be left in the fabric.
22. In a loom, the combination with means for forming a shed and a pair of stake carriers movable together into the shed to insert two weft strands therein, of a plate having two gripping surfaces at the same distance apart as the stake carriers, a slide on said plate having a jaw movable toward and from the two gripping surfaces, and means for operating the slide to grip both strands simultaneously.
23. In a loom, the combination with a supporting frame, a longitudinally reciprocal table carried thereby, and means for reversing the motion of the table at each end of the stroke automatically, of a carrier block fixed on the table, a pair of tubular stake carriers located in said block, one directly over the other, means in each stake carrier for engaging a strand or stake of flexible material and feeding it forward with the stake carrier but not backward when the table reverses, a loom frame adjacent thereto having means for forming a shed, a stake gripper at the opposite end of said loom, means carried by said table for operating said stake gripper at the end of the forward stroke to grip the ends of two stakes projecting from said stake carriers, a pair of cutting devices located on the loom at the side near said supporting frame, and means on the table for operating the cutting devices at the time of the withdrawal of the table to its extreme backward position to cut off the two stakes.
24. In a loom, the combination of a supporting frame, a longitudinally reciprocal carrier block, a pair of tubular stake carriers located in said block, means in the stake carriers for engaging a strand or stake of flexible material and feeding it forward with the stake carrier, a loom frame adjacent thereto having means for forming a shed for receiving the stake carriers, a pair of pivoted shear blades on the side of said loom toward said supporting frame, yielding means for moving them to inoperative position, a notched dial, means operated by the notched dial for positively operating the shear blades, said blades being located in position to engage and cut off the two stakes after they have been deposited in the shed, and means operated by the table upon its withdrawal to its extreme retracted position for rotating said dial far enough to operate the shear blades.
25. The method of weaving twisted paper strands which consists in dividing the warp into a plurality of parts, guiding the warp into the fabric in a plurality of separated parallel planes, engaging the warp strands on opposite sides and pushing them inwardly toward and beyond each other to cross the warp strands, and introducing a plurality of filling strands simultaneously into the crossed warp on opposite sides of the crossing line of the warps.
26. The method of weaving which consists in guiding the warp into the fabric in two planes, forcing the warp strands on each side inwardly toward and beyond the other simultaneously to form a single ply multiple shed, and simultaneously introducing two strands of filling into the double shed on opposite sides of the line of crossing of the two sets of warp strands.
27. The method of weaving which consists in guiding the warp into the fabric in two planes, forcing the warp strands on each side inwardly toward and beyond the other to form a shed, introducing two strands of filling into the shed on opposite sides of the line of crossing of the two sets of warps strands, and at intervals pushing a part of the warp beyond the point of crossing intermittently so that one of the filling strands when introduced will pass on the same side of both sets of warps at points at which the filling has been moved inwardly for producing diamond weaving.
28. The method of weaving which consists in guiding the warp into the fabric in two planes, forcing the warp strands on each side inwardly toward and beyond the other to form a shed, introducing two strands of filling into the shed on opposite sides of the line of crossing of the two sets of warp strands, gripping the ends of the filling at the far side of the loom, withdrawing the shuttles by which they are introduced through the same shed, and cutting off the stakes at the inner side of the loom.
- In testimony whereof I have hereunto affixed my signature.
- OSCAR A. ANDERSON.
